UNITED STATES PATENT OFFICE.

LESLIE W. CLAYBOURN, OF MILWAUKEE, WISCONSIN.

PRINTING MACHINERY.

Application filed May 3, 1926. Serial No. 106,196.

My invention relates to printing machinery, especially to that character of printing presses employed in taking so-called proofs.

5 It is the object of my invention to provide novel means for causing coactive relation between the bed and the tympan cylinder during the printing operation, and separation between said elements during idle 10 passage therebetween; further, to provide novel means for adjusting the distance between said elements of the printing couple for obtaining proper desired printing pressure during the printing; further, to provide 15 novel means for controlling the reciprocations of the reciprocating member of the printing couple; further, to provide novel tripping means for controlling the distance between the members of the printing couple 20 for on-impression relation and for off-impression relation; further, to provide novel means to control the stopping of the reciprocating member at the ends of its paths of travel; and, further, to provide novel means 25 for guiding the reciprocating bed of the printing couple.

The invention will be further readily understood from the following description and claims, and from the drawings, in which 30 latter:

Fig. 1 is a side elevation of my improved device, the paper table being shown in normal position in full lines and in raised position in dotted lines and partly broken 35 away.

Fig. 2 is a plan view of my improved device, partly broken away.

Fig. 3 is a rear end elevation of my improved device, partly broken away.

40 Fig. 4 is a side elevation, partly broken away, showing the gear side of the machine, the gearing being partly in section in the plane of the line 4—4 of Fig. 3.

Fig. 5 is a detail of the brake mechanism, 45 partly broken away, and partly in section on the line 5—5 of Fig. 12.

Fig. 6 is a cross-sectional detail view of the brake, taken in the plane of the line 6—6 of Fig. 5.

50 Fig. 7 is a central longitudinal section, taken on the line 7—7 of Fig. 2, partly broken away.

Fig. 8 is a side elevation of a detail of the end of the feed table and the parts thereon coacting with the impression cylinder. 55

Fig. 9 is a cross-sectional detail of the same, taken on the line 9—9 of Fig. 8.

Fig. 10 is a cross-sectional detail of the same, taken on the line 10—10 of Fig. 8.

Fig. 11 is a cross-section of my improved 60 device, taken on the line 11—11 of Fig. 1.

Fig. 12 is a cross-section of my improved device, taken on the line 12—12 of Fig. 1.

Fig. 13 is a plan view of my improved 65 device, with the reciprocating bed and impression cylinder removed.

Fig. 14 is a side elevation, partly broken away, and partly in section on the irregular line 14—14 of Fig. 11, showing the tripping and adjusting means for the impression cylinder, the impression cylinder being shown 70 in printing relation and at its starting position.

Fig. 15 is a similar view, with the impression cylinder shown in off-impression relation and at its position of completion of 75 printing movement.

Fig. 16 is a longitudinal section of a detail, taken on the irregular line 16—16 of Fig. 11, showing the control means of my 80 improved device in neutral position.

Fig. 17 is a similar view of the same, showing the control means in actuated position.

Fig. 18 is a plan detail of the knock-out 85 means for the control of the bed movements.

Fig. 19 is a cross-section of a detail of the same, taken in the plane of the line 19—19 of Fig. 16.

Fig. 20 is a vertical section, taken on the 90 line 20—20 of Fig. 11, partly broken away, showing the gripper control and the knock-out control when the cylinder and bed are in starting or normal positions.

Fig. 21 is a similar view, showing the bed 95 at its opposite limit of movement.

The frame 31 comprises a rigid runway structure 32, shown as an integral casting, which is trough-shaped in cross-section, and comprises a bottom 33 and upwardly extending sides 34, the bottom being shown reinforced by cross ribs 35 integral with said casting. (See Figs. 3 and 12.) 100

36 and 37 represent the members of the

printing couple, the member 36 being shown as a reciprocating bed and the member 37 as a cylinder. The bed is shown as a form supporting bed, and the cylinder as a tympan cylinder. The bed is shown as a rigid integral casting thoroughly braced by lengthwise ribs 38 and crosswise ribs 39.

The frame is provided with runways 41 and the bed with runways 42, between which 10 roller cages 43 are located. The bed is arranged to be reciprocated on the rollers of said roller cages, with relation to the tympan cylinder.

Lateral positioning of the bed is obtained 15 by means of a guide 44, shown depending from the bed, which coacts with the guideway 45 on the frame, and guides 46, 47. The guides 46, 47, are adjustable with relation to the guideway 45 for adjusting the 20 width of the guiding space between the guideway 45, and the guides 46, 47.

This adjustment is exemplified as accomplished by means of bolts 51 which are adjustably threaded into the frame, as shown 25 at 52. The heads of the bolt coact with the guides 46, 47. Jam-nuts 53 lock the bolts in adjusted positions. Bolts 54 are threaded in the frame, as shown at 55, and extend through slots 56 in the adjustable guides 30 46, 47, for clamping said guides in adjusted positions. These adjustments position the reciprocating bed in lateral directions so as to cause the bed to travel in straight lines back and forth. The guides 46, 47, and their 35 adjusting means, are shown located in a recess 57 in the frame. (See Figs. 11 and 18.)

The bed has a rack 61 fixed to its under side. A pinion 62 meshes with the rack, 40 and is fixed to a shaft 63, journaled in bearings 64 in the main frame. The rack and pinion and lateral guides and adjusting means therefor are located in substantially the middle portion of the width of the frame 45 and bed.

The bed is provided with a form supporting surface 65, for supporting a form 66, secured thereto in suitable manner between cross-strips 67, 68. The bed may be provided with a recess 69 which is located under the inking mechanism 70, when the inking mechanism and the bed are in normal positions.

The inking mechanism is exemplified as 55 comprising an inker frame 71, which has inking rollers mounted therein, which may be suitable construction and arrangement, and may be for instance such as shown, described and claimed in my copending application for patent on improvements in printing machinery, Serial No. 106,197, filed 60 May 3, 1926.

I have exemplified the same in my present 65 application as comprising a central roller 72, form rollers 73 coacting therewith, and

a distributor roller 74 which also coacts with the central inking roller. The inking roller 72 is fixed to a shaft 75 journaled in bearings 76 in the inker frame. Gears 77, 78, are rotatively loose on this shaft, but fixed 70 in axial directions thereon in suitable manner. A clutch-collar 79 is slidable endwise on the shaft and rotates with the shaft. Clutches 81, 82, are located respectively between the clutch-collar and the respective 75 gears 77, 78. A fork 83 is received in an annular groove 84 in the clutch-collar. The fork is arranged to be moved by an endwise movable rod 85, provided with a knob 86, and slidable in bearings 87 in the inker 80 frame. A gear 88 is fixed to a shaft 89 journaled in the inker frame, and meshes with the gear 77. A gear 90 is also fixed to this shaft, and meshes with a gear 91 fixed to a shaft 92 journaled in the inker frame. 85

When the clutch-faces of the clutch 81 are in engagement, the gear 77 is rotatively connected with the shaft 75, thereby connecting the train of gears 77, 88, 90 and 91 with said shaft. 90

The gear 78 meshes with a gear 95 fixed to a shaft 96 journaled in bearings in the inker frame. Gears 97, 98, are also fixed to this shaft, and mesh with racks 99, 100, extending lengthwise of the path of travel 95 of the reciprocating bed, these racks being fixed to the frame of the machine.

A crank handle 101 is arranged to be detachably secured to the shaft 75, as by providing the handle with a socket 102 received over the reduced end of said shaft, a pin 103 in the socket of said handle being received in a slot 104 in the end of said shaft. This construction enables the handle to be readily attached to said shaft for turning 105 said shaft and to be readily removed therefrom.

The cylinder is provided with a gear 111 which meshes with a rack 112 on the reciprocating bed. This gear and rack are in 110 continuous mesh. The cylinder is provided with bearers 113 which rest on bearers 114 on the reciprocating bed. This arrangement insures uniform travel between the impression surface of the cylinder and the 115 printing surface of the form on the bed.

The bed is shown reciprocated by power by means of an electric motor 115, which is preferably a reversible motor, the rotor of 120 which is provided with a sprocket wheel 116. A shaft 117 is journaled in a bearing 118 on a bracket 119 extending from the frame, and in bearings 120, 121, in a housing 122, fixed to the frame. This shaft has thereon a sprocket wheel 123. A sprocket chain 124 is received about the sprocket 125 wheels 116, 123. (See Figs. 3 and 4.)

The shaft 117 has a worm 126 thereon. End thrust bearings 127 are located between this worm and the bearings 120, 121. The 130

worm meshes with a worm wheel 128 fixed to the shaft 63, on which the pinion 62 is also secured.

The inker frame is mounted on rollers 131, which are arranged to travel on guideways 132 on the main frame. The meshing of the gears 97, 98, with the racks 99, 100 maintains the travel of the inker frame in parallelism with the travel of the reciprocating bed. The inker frame is arranged to be secured relatively to the tympan cylinder shown accomplished by means of a hook 135, pivoted to the inker frame, arranged to be releasably received over a pin 136, fixed to 15 the main frame.

During the printing operation, the inker frame is fixed in close association with the tympan cylinder, as by the locking engagement of said hook, in which relation the gear 20 91 thereon is in mesh with the cylinder gear 111, for rotating the inking rollers by the power applied by the cylinder gear 111, so that the rollers will rotate uniformly with the reciprocating movements of the bed. In 25 this relation the clutch 81 is in engagement. In this relation the inking rollers are rotated for distributing the ink and also for applying the ink to the form for the printing operation. In this relation the handle 101 is 30 preferably removed. (See Figs. 1, 2 and 4.)

If it is desired to rotate the inking rollers for distributing the ink without application to the form, the inker frame is moved away from the tympan cylinder, which is accomplished by engaging the clutch 82 and attaching the handle 101 to the shaft 75, and rotating the handle for the desired distance 35 of travel of the inker frame.

The clutch 82 is then disengaged, the 40 clutch collar being left in neutral position. Rotation of the handle will thereupon cause rotation of the inking rollers in the inker frame, while the latter is in the position in which it has been placed.

If it is desired to rotate the inking rollers and also cause travel of the inker frame lengthwise of the reciprocating bed, for instance for preliminarily inking up the form, the clutch 82 is engaged and the handle 101 50 is rotated, whereupon the inking rollers rotate and the inker carriage travels lengthwise of the bed in either direction, according to the direction of rotation of the handle.

The cylinder 37, is provided with axles 55 141, which are journaled in bearings 142 movable in guideways 143 in standards 144 secured to the frame, as by means of bolts 145. The cylinder is positioned endwise by means of nuts 146 threaded over the threaded ends 147 of said axles, washers 148 being interposed between said nuts and the ends of the bearings 142. (See Fig. 11.)

A link 151 is provided at each end of the cylinder, these links being provided with 60 65 bearings 152 respectively received about the

bearings 142. A rock-shaft 153 is journaled in bearings 154 in the main frame, and is provided with an operating handle 155. Eccentrics 156 rock with this rock-shaft, being held rotatively thereto by keys 157. Adjustable eccentrics 158 are received about the eccentrics 156, and are journaled in bearings 159 at the lower ends of the links 151 respectively. These last-named bearings are shown as two-part bearings, the parts of which are 70 adjustably connected by means of bolts 160. A worm 161 is journaled in bearings 162, in a bracket 163, fixed to the bearing 159, the worm meshing with a worm-wheel 164 formed on the eccentric 158, each of the eccentrics 158 being provided with one of these 75 adjustments, and these adjustments being operable independently of one another.

The adjustments of the eccentrics 158 80 adjust the pressure of the printing impression and the parallelism between the axis of the tympan cylinder and the form supporting surface of the bed. The rocking of the rock-shaft moves the cylinder into on-impression relation and into off-impression relation. (See Figs. 11, 14 and 15.)

Means are provided for automatically operating the rock-shaft so as to move the cylinder into on-impression relation throughout the length of travel of the bed in printing direction, and for raising the cylinder into off-impression relation during the reverse movement of the bed.

For accomplishing this I provide one of the eccentrics 156 with an arm 167, on which a roller 168 is journaled, and provide the bed 36 with shoes 169, 170. The shoe 169 is located at the end of the reciprocating bed which is under the cylinder when the bed is in normal position, that is, when its form supporting surface is in exposed relation beyond the tympan cylinder and the inker frame, when the latter is in adjacency to said 95 tympan cylinder. The shoe 170 is at the opposite end of the reciprocating bed.

During the printing movement of the bed, which is in the direction of the arrow *a* shown in Fig. 14, the arm is in depressed relation for depressing the eccentric 156 and depressing the cylinder into its relation of 100 closest approach to the reciprocating bed. This position of the cylinder is maintained during the printing movement of the machine. At the end of said printing movement, the shoe 170 on the bed contacts the roller 168 and moves the eccentric 156, so as to raise the cylinder. The cylinder remains in raised position during the return or reverse movement of the bed into normal 105 position, adjacent to the end of which the shoe 169 strikes the roller 168, and again moves the cylinder into down position, ready 110 for the next impression movement of the bed.

I provide means for definitely and accu- 115 120 125 130

rately arresting the bed at its desired limits of reciprocating movements in opposite directions. For this purpose I have provided a brake 171 and switches 172, 173.

The brake comprises shoes 174, pivoted to a bolt 176 fixed to the housing 122. A spring 177 is received about a rod 178 which passes through said shoes, the rod being shown as a threaded rod with its head at one side of one of the shoes, one end of the spring presented toward the other side of the other of the shoes, and the other end of the spring being held by a nut 179, adjustable on said rod, for adjusting compression of the spring.

15 (See Figs. 3, 4, 5 and 6). The shoes are provided with rollers 180. A releasing block 181 is mounted on a lever 182, pivoted on a rock-shaft 183 journaled in the housing 122.

20 This releasing block is provided with wedge faces 184, 185, arranged to be interposed between said rollers for spreading the brake shoes by movement of the releasing block in either direction. The releasing block 25 is moved for disengaging the clutch for operative movement of the printing press, and is arranged to be moved into braking relation at the moments when the reciprocating bed reaches the end of either 30 of its directions of movement. The shoes are arranged to clamp about a pulley 188, fixed to the shaft 117.

The releasing block 181 is operated by a handle 189, fixed to a rock-shaft 190, having an arm 191 fixed thereto, a link 192 being articulated to said arm at 193, and to an arm 194 at 195. The arm 194 extends from the lever 182. The hub of the arm 191, is provided with a positioning face 196, shown as a flat face, against which a plunger 40 197 is urged by a spring 198 in a socket 199, the walls of which are formed by the main frame, the spring being held in the socket by means of a plug 200 secured to the socket-piece.

An arm 201 is secured to the rock-shaft 190 and has a positioning plate 202 secured thereto. This positioning plate has wedge faces 203, 204, 205, thereon, forming apices 50 206, 207, therebetween. When the positioning plate is rocked for causing coaction of its wedge faces 203 with a roller 208, the positioning plate is in neutral position, and the brake 171 is in engaged relation, the rollers 180 being opposite the reduced portions of the wedge faces on the wedge block 181. The switch operating means comprise the same handle 189 and the rock-shaft 190.

When the operating handle 189 is moved 60 in one direction, the apex 206 passes the roller 208 for setting the switching mechanism for operation of the motor in one direction and for movement of the bed 36 in one direction, and also for movement of the 65 releasing block 181 in one direction for dis-

engaging the brake. When the operating handle 189 is moved in the opposite direction, the positioning plate 202 is first moved into neutral position for neutral position of the switching mechanism and engagement 70 of the clutch, and then for opposite setting of the switching mechanism for rotating the rotor of the motor in the opposite direction and disengagement of the brake and movement of the bed in its opposite direction. 75

The roller 208 is mounted on a lever 209, pivoted to the frame at 210. A plug 211, backed by a spring 212, normally urges the lever and the roller thereon toward the positioning plate. The plug and the spring 80 are located in a socket 213 in the frame. (See Figs. 16, 17).

The arm 201 is provided with a segment gear 215, which meshes with a segment gear 216, on a rocker-part 217, which is journaled about a bushing 218 which forms part of the bearing 154. This rocker-part is provided with rollers 219, 220. The bed 36 is provided with tappets 221, 222, at its respective ends. The tappet 221 coacts with the 90 roller 219, and the tappet 222 coacts with the roller 220, these respective tappets and rollers being in different vertical planes, parallel with the path of travel of the bed, (see Figs. 16, 17, 18 and 19) so that they do 95 not interfere with each other in their operative functions. These tappets and rollers and the rocker-part are provided for automatic tripping of the switching mechanism and brake. When the bed is in neutral position, the rocker frame has been rocked for placing the switching mechanism in neutral relations and the brake in braking relation.

The motor 115 is a reversible motor, controlled in opposite directions of rotation by 105 the switches 172, 173. These switches are normally open switches, and are respectively controlled by operating arms 223, 224, on which rollers 225, 226, are located. These arms are normally spring-pressed toward an 110 operating arm 227, by means of springs 228, 229. The operating arm 227 is secured to the shaft 183, to which the lever 182, which controls the brake, is also secured. When the arm 227 is moved in one direction, one 115 of the switches is closed for energizing the motor for rotation of its rotor in one direction, and when the arm 227 is moved in opposite direction from its neutral position, the other of said switches is closed, for rotating 120 said rotor in the opposite direction, and thereby controlling the direction of movement of the bed, and consequently the direction of rotation of the cylinder and of the inking rollers, when the latter are geared to 125 the cylinder.

The rocker-part and tappets are also so related that the switches are placed in neutral positions at the respective ends of travel of the bed. The handle 189 can then be 130

5 moved only in a direction which will energize the electric motor in the opposite direction for reverse movement of the bed, as a matter of safety, to prevent overrunning of the bed in either direction. Thus, referring to Fig. 16, which represents the bed in its normal position, the tappet 221 is shown in interfering relation with the roller 219, so as to prevent rocking of the rocker-part in one 10 of its directions of movement. The operating handle 189 can therefore be moved only in one direction, which will correspond to the closing of the switch to actuate the electric motor in a direction to cause travel of the bed in the direction of the arrow *b*. This 15 means a rocking of the rocker-part so as to move the roller 220 upwardly. The bed thereupon travels in the direction of the arrow *b*, the tappet 221 passing the roller 220, because said tappet is in a different vertical 20 plane from that in which said roller 220 is located.

At the opposite end of the path of the bed, the tappet 222 strikes the roller 220, for returning the rocker-part and the operating handle 189 to normal positions, and thereby also placing the arm 227 in normal position, for neutral relations of the switches, the releasing block 181 being also returned to neutral position, for instantly clamping the 30 brake and stopping the travel of the bed and the rotation of the cylinder at definite positions, corresponding to the positions of the parts shown in Fig. 21. If it is desired to move the bed in the opposite direction, the handle 189 is rocked in the opposite direction, placing the parts in the relation shown in Fig. 17, and causing travel of the bed in the direction of the arrow *c*.

40 The rocking of the rocker-part into such position also shifts the releasing block for release of the brake. In this relation, the roller 219 is passed by a recess 230 in the block on which the tappet 222 is formed.

45 At the end of the reverse travel of the bed, the tappet 221 strikes the roller 219, for returning the rocker-part and consequently its operating arm and the releasing block 181 and the switch operating arm 227, to neutral 50 positions, for deenergizing the motor and applying the brake, so as to arrest the movements of the bed and tympan cylinder in definite positions, such as exemplified in Figs. 16 and 20.

55 Grippers 236 are mounted on a rock-shaft 237 journaled in the tympan cylinder. The grippers are adjustable lengthwise on said rock-shaft and are arranged to be clamped in adjusted positions by usual clamp-bolts 238. (See Figs. 2, 7, 11, 20 and 21.) A spring 60 239 normally urges gripping relation of said grippers in usual manner. The spring surrounds a rod 240, articulated at 241 to an arm 242, fixed to the rock-shaft 237, and slideable at its other end in a bearing 243 fixed

to the end wall of the cylinder. The arm 242 has a shoe 244 formed thereon, which is arranged to contact a block 245, fixed to the bed 36, as by means of screws 246. The co-action between this block and shoe opens the 70 grippers at the position of rest of the tympan cylinder upon the completion of the printing movement of the bed, so that a printed sheet, which has been gripped by the grippers, is released, in order that it may be 75 removed from the cylinder.

The paper to be printed is fed to the cylinder from a paper table 251, being guided and positioned by proper gauges, exemplified as an adjustable side gauge 252, and end 80 gauges 253, which latter are adjustably secured to a cross-shaft 254, on which the usual clamps 255 for the ends of the tympan sheets are also located.

A lever 257 is pivoted at 258 to a lug 259 on the standard 144. This lever is of arcuate form, and has one end of a link 261 articulated therewith at 262, the other end of the link being articulated at 263 to a treadle-arm 264, pivoted at 265 to the main frame, (see 90 Figs. 3, 20 and 21) and having thereon a treadle 266.

The lever 257 is provided with a contact-part, shown as a pin 267, which is arranged to engage the shoe 244, when the tympan cylinder is in normal position, and the treadle is depressed, for rocking the gripper shaft and opening the grippers, to permit the feeding of a sheet against the gauges. Release of the treadle closes the grippers, 95 whereupon the printing operation is performed, the grippers being released at the completion of the printing operation, exemplified in Fig. 21, so that the printed sheet 100 may be removed from the tympan cylinder, the tympan cylinder making approximately one and one-third revolutions in the printing operation, and a similar number of revolutions in reverse direction upon return of the bed and the tympan cylinder to their 110 normal positions, exemplified in Fig. 20.

Paper guides 271 received part-way around the cylinder are adjustable lengthwise of the cylinder on a cross-rod 272, the cross-rod being secured in brackets 273 extending from the standards 144. These guides guide the paper about the cylinder and prevent dropping of the paper away from the cylinder for preventing soiling thereof. 120

A further guiding means for the paper is mounted on the paper table, and consists of rollers 275 mounted on arms 276, adjustable to selected positions lengthwise of a rock-shaft 277, as by means of set-bolts 278. 125 The rock-shaft is journaled in bearings 279 of side frames 280, hinged on a shaft 281, mounted in bearings 282, of pedestals 283, at the respective sides of the main frame, for permitting swinging of the table up- 130

wardly away from the cylinder, as shown in dotted lines in Fig. 1.

An arm 285 is fixed to the rock-shaft 277. This arm is normally urged for rocking the rock-shaft to cause engagement of the rollers 275 with the outer surface to the tympan cylinder, shown accomplished by means of a plunger 286, the end of which is received in a socket 287 in said arm, the 10 plunger being provided with a stem 288 having a pull-knob 289 thereon. The plunger operates in a socket 290 of an adjustable bolt 291, adjustable in a lug 292 extending from the side frame. An adjustable stop screw 15 293 is threaded in the side frame, and is held in adjusted position by a jam-nut 294. This stop screw limits the approach of the rollers 275 toward the tympan cylinder. The adjustment of the bolt 291 limits the 20 movement of the plunger toward the arm 285, and adjusts the tension of a spring 295, which urges the plunger toward the arm 285.

These adjustments control the approach of the rollers 275 toward the tympan cylinder and the pressure thereof upon the sheet being printed. (See Figs. 7, 8 and 9).

The approach of the paper table toward the tympan cylinder is controlled by stop-screws 296, at the respective sides of the 30 table, these stop-screws being adjustable in the pedestals 283, and held in adjusted positions by jam-nuts 297.

A plunger lock 301, having a tapered end 302, is received in a socket 303 in the side frame of the paper table, the socket having a tapered face coacting with the plunger. (See Figs. 8 and 10.) The plunger is located in a socket 305 in the pedestal 283, and is provided with a stem 306, which has a handle 307 at its outer end. A spring 308 is located between the plunger and the bottom of the socket for normally urging the plunger into engagement with the side frame of the table, for holding the table in down position.

My improved device provides novel and accurate means for printing sheets of paper, especially in taking proofs; and provides simple means whereby the sheets of paper 50 may be accurately positioned upon the cylinder and clamped in such accurate position; provides simple and accurate means whereby the travel of the bed and rotation of the cylinder are controlled, and cessation of 55 movements thereof compelled at definite positions; provides novel means for adjusting pressures of the impressions and controlling the approach and recession of the cylinder with relation to the bed; insures the desired 60 proper inking of the form; provides combined control of the electric motor for driving the machine and the brake for the same, and provides automatic controls for the approach and recession of the cylinder, and for

operative movements of the same and of the 65 bed.

Having thus fully described my invention, what I claim as new, and desire to secure by Letters Patent, is:

1. In a printing machine, the combination 70 of a printing couple comprising a bed and a cylinder, and positioning means for said cylinder comprising a link having a bearing about the axis of rotation of said cylinder and a second bearing, an eccentric in said 75 second bearing, operating means connecting with said eccentric and means on said bed automatically controlling said eccentric.

2. In a printing machine, the combination 80 of a printing couple comprising a reciprocating bed and a rotating cylinder geared together, and positioning means for said cylinder comprising a link having a bearing about the axis of rotation of said cylinder and a second bearing, nested eccentrics in said 85 second bearing, a handle for operating an inner one of said eccentrics for raising and lowering said link, and adjusting means on said link for rotatively adjusting the other of said eccentrics.

3. In a printing machine, the combination 90 of a printing couple comprising a bed and a cylinder, and positioning means for said cylinder comprising a link having a bearing about the axis of rotation of said cylinder and a second bearing, nested eccentrics in 95 said second bearing, operating means connecting with one of said eccentrics, the other of said eccentrics provided with a worm-wheel, and a worm journaled in said link 100 meshing with said worm-wheel for rotatively adjusting said other of said eccentrics.

4. In a printing machine, the combination 105 of a printing couple comprising a bed and a cylinder, and positioning means for said cylinder comprising a link having a bearing about the axis of rotation of said cylinder and a second bearing, nested eccentrics in 110 said second bearing, an arm on one of said eccentrics, manual operating means for rotating said last-named eccentric to respectively cause approach and recession of said cylinder with relation to said bed, means on said bed for moving said arm in opposite directions adjacent the limits of opposite 115 movements of said bed, and means for rotatively adjusting the other of said eccentrics.

5. In a printing machine, the combination 120 of a printing couple comprising a bed and a cylinder, and positioning means for said cylinder comprising a link having a bearing about the axis of rotation of said cylinder and a second bearing, an eccentric in said 125 second bearing, an arm on said eccentric, manual operating means for rotating said eccentric to respectively cause approach and recession of said cylinder with relation to

said bed, and means on said bed for moving said arm in opposite directions adjacent the limits of opposite movements of said bed.

6. In a printing machine, the combination 5 of a printing couple comprising a bed and a cylinder, and positioning means for said cylinder comprising links at the respective ends of said cylinder, a bearing on each of said links about the axis of rotation of said cylinder, a second bearing on each of said links, operatively connected eccentrics in said last-named bearings, an operating part extending therefrom, and means on said bed arranged to move said operating part in opposite directions adjacent the limits of opposite movements of said bed, said means maintaining said operating part against reverse movements during rest positions of said bed at said limits of opposite movements.

20 7. In a printing machine, the combination of a printing couple comprising a bed and a cylinder, a bearing for each end of said cylinder, a link at each end of said cylinder comprising bearings about said first-named 25 bearings, bearings at the other ends of said links, a pair of nested eccentrics in each of said last-named bearings, operating means connecting with one of the eccentrics of each of said pairs for raising and lowering said first-named bearings, and independent adjusting means connecting with the other eccentric of each of said pairs of eccentrics.

35 8. In a printing machine, the combination of a printing couple comprising a bed and a cylinder which are geared together, an electric motor for driving the same, electric translating means for controlling the operation of said motor, and means for operating said translating means comprising an 40 actuated member having a neutral position and arranged to be operated in opposite directions from said neutral position, and tappets on said bed coacting with said actuated member so placed as to move said actuated member in opposite directions adjacent to the limits of opposite reciprocating movements of said bed and at said limits to move into interfering relation with said actuated member to interfere with opposite movements of said actuated member at each of said limits.

45 9. In a printing machine, the combination of a printing couple comprising a bed and a cylinder which are geared together, an electric motor for driving the same, electric translating means for controlling the operation of said motor, means for operating said translating means comprising an actuated member having a neutral position and 50 arranged to be operated in opposite directions from said neutral position, tappets on said bed coacting with said actuated member so placed as to move said actuated member in opposite directions adjacent to the limits of opposite reciprocating movements of said

bed and at said limits to move into interfering relation with said actuated member to interfere with opposite movements of said actuated member at each of said limits, and an operating handle for said actuated 70 member.

10. In a printing machine, the combination of a printing couple comprising a bed and a cylinder which are geared together, an electric motor for driving the same, electric translating means for controlling the operation of said motor, means for operating said translating means comprising an actuated member having a neutral position and arranged to be operated in opposite directions 75 from said neutral position, tappets on said bed coacting with said actuated member so placed as to move said actuated member in opposite directions adjacent to the limits of opposite reciprocating movements of said bed and at said limits to move into interfering relation with said actuated member to interfere with opposite movements of said actuated member at each of said limits, a 80 brake, and means connecting said actuated member with said brake, whereby to cause braking action in said brake during neutral positioning of said actuated member and release relation in said brake during said 85 movements of said actuated member in said opposite directions.

11. In a printing machine, the combination of a printing couple comprising a bed and a cylinder which are geared together, driving means for the same including an electric motor, electric translating means for controlling the operation of said motor, a 100 brake for said driving means, and means for operating said translating means and said brake comprising a handle, automatic positioning means for the same, and connecting means between said handle and said translating means and said brake, whereby to place said translating means in neutral 105 relation and said brake in braking relation by neutral positioning of said handle, and to operate said translating means and release said brake by movements in opposite directions of said handle.

110 12. In a printing machine, the combination of a printing couple comprising a bed and a cylinder which are geared together, a reversible electric motor for driving the same, electric translating means for controlling the operation of said motor in opposite 115 directions, a rockable member, means for normally holding said rockable member in neutral position, a handle for manually rocking said rockable member, said bed provided with means for moving said rockable member in opposite directions adjacent to the limits of opposite movements of said bed, and means resiliently holding said handle in neutral position.

13. In a printing machine, the combina- 120 125 130

- tion of a printing couple comprising a bed and a cylinder which are geared together, and means for controlling the reciprocations of said bed comprising a rock-shaft, a handle therefor, means resiliently holding said rock-shaft in actuated positions, a rockable member, gearing between said rock-shaft and said rockable member, and means on said bed for automatically rocking said rockable member and forming obstructing means for obstructing reverse movements of said rockable member.
14. In a printing machine, the combination of a printing couple comprising a bed and a cylinder which are geared together, positioning means for said cylinder comprising a link at each end of said cylinder, each of said links having a bearing about the axis of rotation of said cylinder and a second bearing, eccentrics in said second bearings connected for combined rockable movements, a rockable member about the axis of rotation of said eccentrics, driving means for said machine controlled by said rockable member, and actuating means on said bed for automatically rocking said eccentrics and said rockable member.
15. In a printing machine, the combination of a printing couple comprising a bed and a cylinder which are geared together, positioning means for said cylinder comprising a link at each end of said cylinder, each of said links having a bearing about the axis of rotation of said cylinder and a second bearing, eccentrics in said second bearings connected for combined rockable movements, a rockable member about the axis of rotation of said eccentrics, driving means for said machine controlled by said rockable member, and actuating means on said bed for automatically rocking said eccentrics and said rockable member.
16. In a printing machine, the combination of a printing couple comprising a bed and a cylinder which are geared together, positioning means for said cylinder comprising a link at each end of said cylinder, each of said links having a bearing about the axis of rotation of said cylinder and a second bearing, eccentrics in said second bearings connected for combined rockable movements, a rockable member about the axis of rotation of said eccentrics, driving means for said machine controlled by said rockable member, actuating means on said bed for automatically rocking said eccentrics and said rockable member, and independent manual means for respectively rocking said eccentrics and said rockable member.
17. In a printing machine, the combination of a printing couple comprising a bed and a cylinder which are geared together, positioning means for said cylinder comprising a link at each end of said cylinder, each of said links having a bearing about the axis of rotation of said cylinder and a second bearing, eccentrics in said second bearings connected for combined rockable movements, a rockable member about the axis of rotation of said eccentrics, driving means for said machine controlled by said rockable member, actuating means on said bed for automatically rocking said eccentrics and said rockable member, and braking means for said driving means having operative connection with said rockable member.
18. In a printing machine, the combination of a printing couple comprising a bed and a cylinder which are geared together, grippers on said cylinder, means for arresting said bed at the end of its printing movement, and means between said bed and said grippers coacting at said end of said printing movement to release said grippers.
19. In a printing machine, the combination of a printing couple comprising a bed and a cylinder which are geared together, grippers on said cylinder, a shoe having connection with said grippers for operating the latter, an arcuate lever pivoted at the end of said cylinder, a treadle for operating the same, said arcuate lever provided with a coacting part coacting with said shoe for releasing said grippers upon actuation of said treadle, and means between said bed and said shoe automatically coacting at the end of the printing movement of said bed to release said grippers.
20. In a printing machine, the combination of a printing couple comprising a bed and a cylinder which are geared together, a paper feed table, and means thereon in rear of the delivery end of said table arranged to bear upon the fed sheet after being printed.
21. In a printing machine, the combination of a printing couple comprising a bed and a cylinder which are geared together, a paper feed table, paper guiding means about said cylinder between said table and said bed, grippers on said cylinder, and means between said bed and said grippers automatically coacting at the end of printing movement of said bed to release said grippers, whereby to permit withdrawal of the printed sheet from said grippers and guides.
22. In a printing machine, the combination of a printing couple comprising a bed and a cylinder which are geared together, a paper feed table, a rock-shaft thereon, arms adjustably secured to said rock-shaft projecting toward said cylinder, rollers on said arms coacting with said cylinder in rear of the delivery end of said table, and grippers on said cylinder in advance of the

delivery end of said table when said cylinder is in normal position, and arranged whereby said cylinder makes more than a complete revolution in printing a sheet, said 5 rollers arranged to bear upon the printed sheet during the latter portion of said rotation of said cylinder.

23. In a printing machine, the combination of a printing couple comprising a bed 10 and a cylinder which are geared together, a paper feed table, a rock-shaft thereon in rear of the delivery end of said paper feed table, arms on said rock-shaft extending toward said cylinder, rollers on said arms 15 coacting with said cylinder and arranged to bear upon the fed sheet after being printed, and resilient means urging said rollers toward said cylinder.

24. In a printing machine, the combination of a printing couple comprising a bed 20 and a cylinder which are geared together, a paper feed table, a rock-shaft thereon in rear of the delivery end of said paper feed table, arms on said rock-shaft extending 25 toward said cylinder, rollers on said

arms coacting with said cylinder and arranged to bear upon the fed sheet after being printed, resilient means urging said rollers toward said cylinder, and adjustable means limiting approach of said rollers toward said cylinder. 30

25. In a printing machine, the combination of a printing couple comprising a bed and a cylinder which are geared together, a paper feed table, a rock-shaft thereon in rear of the delivery end of said paper feed table, arms on said rock-shaft extending toward said cylinder, rollers on said arms coacting with said cylinder and arranged to bear upon the fed sheet after being printed, adjusting means limiting approach of said rollers toward said cylinder, and adjustable resilient means coacting with said last-named adjusting means for resiliently urging approach of said rollers toward said 40 cylinder. 45

In testimony whereof, I have hereunto signed my name.

LESLIE W. CLAYBOURN.
